(57) **CLAIM**

(**) Term: **14 Years**

An ornamental design for a fifty-five compartment socket tray, as shown and described.

(21) Appl. No.: **29/155,598**

DESCRIPTION

(22) Filed: **Feb. 13, 2002**

FIG. 1 is a perspective view of the fifty-five compartment socket tray according to the subject invention.

(51) LOC (7) Cl. **03-01**

FIG. 2 is a side view of the fifty-five compartment socket tray in FIG. 1.

(52) U.S. Cl. **D3/305**

FIG. 3 is a vertical section along line 3—3 of the fifty-five compartment socket tray in FIG. 1.

(58) Field of Search D3/304, 313, 314,

FIG. 4 is a front view of the fifty-five compartment socket tray in FIG. 1.

D3/315, 201, 901, 905; 206/557, 558, 561—565,

FIG. 5 is a rear view of the fifty-five compartment socket tray in FIG. 1.

391, 372, 327, 376—378, 389; D19/75,

FIG. 6 is a vertical section along line 6—6 of the fifty-five compartment socket tray in FIG. 1.

92; 248/314; 211/70.6; 220/500, 507; D8/71;

FIG. 7 is a top view of the fifty-five compartment socket tray in FIG. 1; and,

D9/347

FIG. 8 is a bottom view of the fifty-five compartment socket tray in FIG. 1.
